(57) **CLAIM**

The ornamental design for a cap for a chlorinator retrofit assembly, as shown and described.

DESCRIPTION

FIG. 1 is top perspective view of a cap for a chlorinator retrofit assembly showing my new design.

FIG. 2 is a top view thereof.

FIG. 3 is a bottom view thereof.

FIG. 4 is a front view thereof, the back view being a mirror image thereof; and,

FIG. 5 is a right side view thereof, the left side view being a mirror image thereof.

The broken line showing of a cap for a chlorinator retrofit assembly is included for purposes of illustrating portions of the article and do not form any part of the claimed design.

1 Claim, 4 Drawing Sheets
